UNITED STATES PATENT OFFICE.

ALFRED E. WALLER, OF MOUNT VERNON, NEW YORK, ASSIGNOR TO WARD LEONARD ELECTRIC COMPANY, A CORPORATION OF NEW YORK.

RESISTANCE DEVICE.

1,373,689.

Specification of Letters Patent.

Patented Apr. 5, 1921.

Application filed March 3, 1919. Serial No. 280,293.

To all whom it may concern:

Be it known that I, ALFRED E. WALLER, a citizen of the United States, residing at Mount Vernon, in the county of Westchester and State of New York, have invented certain new and useful Improvements in Resistance Devices, of which the following is a specification.

This invention relates to electrical resistance devices and particularly to the current carrying resistor elements of rheostats and the like. One object of the invention is to provide a resistance device in which the resistor units will be strong, light and self-supporting and readily adaptable to a wide variety of uses.

In my invention I employ resistor elements of thin strip metal shaped to be permanently rigid and self-supporting when in place and yet allowing for free expansion and contraction under temperature changes. At the same time the shaping of the units is such that before assembly and attachment they are easily flexed into different forms to be variously positioned and combined to meet different commercial requirements. Other advantages of this invention especially in cheapness of manufacture and durability in service will appear from the following description of various embodiments taken in connection with the accompanying drawings, in which—

Figures 1, 2, 3 and 4 are perspective views showing the formation of a resistor element for one embodiment of the invention.

Fig. 5 is a plan view with top removed of a rheostat showing one embodiment of my invention.

Fig. 6 is a vertical section of Fig. 5.

Fig. 7 is a diagram illustrating the resistor element connections of the rheostat of Figs. 5 and 6.

Figs. 8 and 9 are rear and side views respectively in vertical section of another embodiment of the invention.

Fig. 10 is a perspective view of a detail of the apparatus of Figs. 8 and 9.

Figs. 11 and 12 are rear and side views respectively illustrating another modified form of resistance embodying the invention.

Fig. 13 is a diagram illustrating a further modification of the invention to form a fixed resistance unit.

Fig. 14 is a plan view of another embed-

ment of the invention illustrating a further modification, and

Fig. 15 is a perspective view of a resistor element of the modification of Fig. 14.

In the embodiments of the invention illustrated in the drawings the resistor element for the rheostat or other resistance device is formed from a continuous strip or ribbon 20 of resistant metal of suitable cross section, from which the resistor element may be formed and cut off at a single operation, or it may be formed in the successive steps shown in Figs. 1 to 4 of the drawing. The metal strip is longitudinally stiffened as by turning up the side flanges 21, and at certain desired portions as 23, 24 and 25, Fig. 3, are provided flat, unstiffened relatively flexible sections which are bent to form the piece into a unit of resistor element such as shown in Fig. 4 having longitudinally stiff supporting portions 26, 27 and adjacent flexed portions to permit the stiffened portions and the end points of attachment to be variously adjusted. The relative number and arrangement of the flexed and stiff portions in each element may be widely varied. In the form of resistor unit shown, Fig. 4, a middle bend 24 intervenes between the ends 23 and 25 which in assembled position form feet provided with holes 28, 29 for fastening to posts or taps on a rigid base. The two channeled legs 26 and 27 of the V are stiff in all directions and are connected by the portion 24 made rigid by its connecting position between the solidly held leg portions. When thus attached the unit unyieldingly holds its shape against strain in any direction and is completely self-supporting. At the same time it permits of free expansion and contraction under temperature changes so as to maintain its permanently rigid support without looseness and without troublesome allowances for differing lengths. The unit is also easily attached in place on panel boards or panel strips and easily fitted to different arrangements of binding posts or taps as shown in Figs. 5 to 15 of the drawings, so that the structure and assembly of the entire resistance device is made simple and easy and a single line of standard units may be used in different types of resistance devices.

In Figs. 5 and 6 the resistance device or rheostat showing one embodiment of this in-

vention comprises a casing 30 within which is the vertical panel 31 carrying on its front face the controller arm 33 and contacts 32, and on its rear face the resistor elements 37, 39 connected to contacts as indicated in diagram in Fig. 7. The current passes from one terminal 36 through the permanent or residual resistor elements 37 in series on posts *a*, *b*, *c*, etc., and thence to the post *l* and such of the resistor elements 39 on posts *l*, *m*, *n*, etc., as are interposed in the circuit by the position of the controller arm 33 which is pivoted at 34 and connected to the other terminal 40.

15 The resistance units 37, 39 are of the type illustrated in Fig. 4 and are assembled in series on posts or taps carried by the panel 31. The elements 37 are zig-zagged back and forth in series between posts *a*, *b*, *c*, etc., and have their feet 23, 25, fastened to said posts which are so spaced that where two feet of adjacent elements are fastened to the same post the legs have to be twisted around their longitudinal axes as shown at 45 to bring 25 the overlapping feet at right angles to each other and avoid interference. Similarly the elements 39 are connected in series to the posts *l*, *m*, *n*, etc., with their channeled portions twisted to put their ends on the posts. 30 This twist accommodates the units to a close spacing of the posts and is readily given to the unit legs when they are being assembled, since the channeled stiffening still leaves the legs easily twisted, while the curved intermediate bend is stiff against such twisting 35 and is not warped thereby.

For certain cases where it is desirable to assemble the units very close together, and where exceptional rigidity is desired intermediate bends of the resistor units may be separated by insulating washers 46 threaded on rods 47 passing through these end bends, and insulating sleeves may also be provided on the rod and between the washers to insulate the units from the rods. With nuts 48 set to bind these parts together a unitary rigid structure is formed in which each part supports every other yet all are free to expand and contract under temperature changes. 45 The resistors are uniformly spaced and well ventilated and it is obvious that with this construction another opposite board may be combined with rows of resistors oppositely directed and intervening between the ones 50 shown.

55 In connection with many panels as for instance those for portable resistance boxes it is desirable to have the resistors spread out flat against the back of the panel with only very slight depth. To such situations the resistor element of this invention is readily adapted. In Figs. 8, 9 and 10 there is shown a modified form of resistance in which a vertical control panel 50 has rows of contact studs 51, 52, 53 and 54 connected respec-

tively to resistor units 55, 56, 57, 58 at the rear of the panel by posts 60 passing through the panel. These posts are long enough to properly spread the ends of the resistor units which are connected zig-zag to the end 70 of one post and base of the next as shown in perspective in Fig. 10 where the first unit 55 is connected to the end of post 51', the remaining units 55 being similarly connected. The other sets of resistor elements 56, 57 and 75 58 are similarly connected to their respective lines of posts and as to elements 56 and 57 these sets overlap at the center with set 56 in front of set 57. This overlap economizes space and is accomplished by relatively bending each set of elements or by spacing the end perforations of legs farther from the middle bend. In this modification of the invention the ends of the elements are clamped between nuts 59, 60 and spaced 80 apart by sleeves 61 fitting on the posts and these sleeves are of sufficiently small diameter to fit between the side flanges 21 so that these flanges may be carried to the extreme ends of the legs. Through the outer ends of 85 each set of elements is threaded a connecting rod 65 carrying spools 66 (see Fig. 10) insulating the elements from the rod and disks 67 insulating the elements from each other. Each set of elements is separately and firmly 90 self supporting and all are free to expand and contract as necessary to accommodate temperature changes without straining or warping the parts. The contacts 51, 52, 53, 54 may of course be arranged in circuit as 95 desired and the resistance varied by pieces 63 sliding along the rows of contacts.

In Figs. 11 and 12 the support 70 has contact studs 71 on its front face and connected with these studs a row of alternating 105 short posts 72 and long posts 73 to which the resistance elements 75 are fastened, each element connecting the base of a post 72 with the top of the adjacent post 73 so as to form a series of rigid self-supporting loops with 110 each half loop connected to a post. In this construction, the resistor elements in series may be integral with each other so that a number of loops may be the same strip of metal without cutting and separating the 115 units. In forming such resistors a series of units could be integral with each other simply stamped up out of the metal strip continuously without cutting and later cut into clusters of the desired number of units 120 which would be bent into the series of loops fitted onto the posts.

In Fig. 13 a number of such clusters are shown assembled in a different manner to form a permanent resistance between terminals 80 and 86. In this modification two successive V units are formed integrally at such locations as between points 101 and 102, there being only a single thickness of metal under the intermediate clamping nut 130

87. Thus the part between points 101 and 102 may be said to be W-shaped.

In Figs. 14 and 15 resistor units 89 of this invention are illustrated connected to a series of closely spaced taps 90, 91, 92, 93, etc., arranged on the arc of a circle *m* for co-operation with a pivoted controller arm. In this modification the elements extend at right angles to the base 96 and the legs 94 of the elements must be considerably twisted around their longitudinal axes as shown in Fig. 15 with the feet 95 brought close together in a very compact manner.

It will be seen that my improved resistor elements are free from the disadvantages attending the use of flexible wires or strips which are not effectively self-supporting and may require insulating supports and spacers. Also my resistor elements are not subject to the risk of breakage like cast metal grids, and they can be made thinner in cross section and hence of higher resistance and lighter weight than for cast metal grids.

25 The resistor element of this invention is easily and cheaply manufactured. The stock is plain ribbon of any suitable metal or resistance alloy. From this there is machine formed the complete resistor by simple bending and cutting operations involving no wastage of metal. The final shape of the resistor element is such that it may be directly formed from the strip and the units are assembled simply by fastening them in place on the posts without any special holding means or supporting frames, and without complicated folding or soldering of the units in place. The intermediate flexed portion and the stiffened legs permit the unit to 40 be adapted to a wide variety of uses while assuring a rigidly self-supporting yet freely expanding and contracting structure when assembled. A single line of resistor stock serves for many different devices reducing 45 the amount of stock to be kept on hand. The preferred flanged channel form of stiffening is simple to make and of great strengthening effect compacting the strip in section and permitting the stock to be very thin 50 and of great area and radiating power. In many types of devices such as those in Figs. 8 to 15 these resistor elements may be directly fastened to the contact taps without intervening leads and this together with the 55 absence of spaced supporting frame work produces a simple, light and highly efficient construction.

I claim:—

1. In a resistance device, a supporting 60 panel, a plurality of resistor elements comprising strips having stiffened lengthwise portions connected by unstiffened bent portions, and supports for said strips mounted on said panel laterally displaced from each 65 other and connected with the ends of said

strips, which ends are separated from said bent portions by the intervening stiffened lengthwise portions.

2. In a resistance device, a supporting panel, a plurality of resistor elements of 70 bent strip metal comprising self-supporting stiffened lengthwise portions extending at an angle to each other and having flexible connections between said stiffened portions permitting relative positioning and free expansion and contraction of said stiffened portions, and laterally spaced supports on said panel for supporting said strips.

3. In a resistance device, a supporting panel, a plurality of resistor elements extending outwardly from said panel comprising supporting end portions with stiffened lengthwise portions intervening between said end portions, and unstiffened bent portions intervening between said stiffened portions, 85 and laterally spaced supports on said panel for supporting said elements by engagement with said end portions.

4. In a resistance device, a supporting panel, a resistor element outwardly extending 90 from said panel, comprising an integral ribbon of metal bent to form stiffened lengthwise portions, and an unstiffened portion intervening between said stiffened portions so that said stiffened portions may be relatively positioned by bending said unstiffened portion, and supports on said panel for said element laterally spaced from each other and connected to portions of said ribbon which are separated from said unstiffened bent portion 95 by the intervening stiffened lengthwise portions.

5. In a resistance device, a supporting panel, a resistor element having stiffened lengthwise portions at an angle to each other 105 and having a connecting relatively flexible portion between said stiffened portions adapted to bend to permit relative positioning and free expansion and contraction of said stiffened portions, and supports for said 110 element on said panel spaced from each other and located at the separated ends of the angularly related stiffened portions of said element.

6. In a resistance device, a panel, a plurality of rows of posts on said panel, and resistance elements attached to said posts, said elements having self-supporting lengthwise portions outwardly extending from said panel and having the lengthwise portions of each element at an angle to each other and having a flexible connection between the self-supporting portions, and said elements also having their most separated parts attached to said posts.

7. A resistance element comprising a long thin narrow sheet metal strip bent with respect to a longitudinal axis to give it stiffness, and bent with respect to a transverse axis to space the longitudinal stiffened por- 130

- tions at an angle to each other to form a V-shaped element, a support, and means on said support to which the separated ends of said V-shaped element are connected: 60
- 5 8. A resistance device comprising a supporting panel, posts mounted on said panel and spaced from each other, a plurality of resistance elements of long thin narrow sheet metal having two points of each of said elements attached respectively to said posts, each of said elements having longitudinal portions extending outwardly from said panel and bent with respect to a longitudinal axis to give it stiffness and bent at an intermediate portion with respect to a transverse axis and having the longitudinal portions spaced at an angle to each other, each of said elements being supported on said posts at the most widely separated points of the element, and a movable contact device for varying the number of said elements in circuit. 65
- 10 9. A resistance device comprising a supporting panel, two sets of posts mounted on said panel, a plurality of resistance elements supported by said posts, each of said elements extending outwardly from said panel and comprising a thin metal strip having stiffened lengthwise portions connected together at their outer ends, said stiffened portions being angularly related to each other and having the separated ends of said elements connected respectively to one of the posts of each of said sets. 70
- 15 10. A resistance device comprising a panel, two posts on said panel, and a V-shaped metal strip having the legs bent longitudinally to form stiffened portions connected together at the apex and extending outwardly from said panel, each of said legs being bent at the separated ends of the element to form a supporting foot extending parallel to the plane of said panel, said feet being connected respectively to said posts. 75
- 20 11. A resistance device comprising a panel, two sets of posts on said panel, and a resistance element of metal ribbon comprising stiffened portions having their edges flanged at an angle to the body of the ribbon and an intermediate unflanged portion bent to position said stiffened portions at an angle to each other, the widely separated portions of said angularly related stiffened portions being connected respectively to said sets of posts. 80
- 25 12. A resistance device comprising a panel, two sets of posts on said panel, and resistance elements supported by said posts, each of said elements extending outwardly from said panel in a plane substantially perpendicular thereto and comprising longitudinally stiffened metal strips forming lengthwise portions at an angle to each other and connected at their outer ends and supported at their inner separated ends on said two sets of posts respectively. 85
- 30 13. A resistance device comprising a panel, a plurality of posts on said panel spaced from each other, resistance strips supported on said posts and extending outwardly from the back of said panel and having longitudinal portions of thin metal strips longitudinally stiffened and connected at their outer ends and having their inner ends mounted on said posts, and a movable contact device on the front of said panel for varying the amount of resistance in circuit. 90
- 35 14. A resistor element adapted to be formed from a metal ribbon and comprising portions longitudinally stiffened and connected by a plane bend, said stiffened portions being twisted around their longitudinal axes without warping said bend, and means for connecting said stiffened portions to a support. 95
- 40 15. A resistor element adapted to be formed from metal ribbon and comprising portions longitudinally stiffened and connected by a plane bend, said stiffened portions being twisted around their longitudinal axes without warping said bend, and means for connecting said stiffened portions to a support comprising relatively flexible feet members extending from the ends of said portions. 100
- 45 16. In a resistance device the combination with a plurality of taps in the same plane, of resistor elements connected to said taps and extending perpendicular to said plane comprising portions attached to said taps, self supporting legs extending from said attached portions and bent portions connecting said legs. 105
- 50 17. In a resistance device the combination with a series of taps, of resistor elements connected between said taps and comprising longitudinally stiffened portions twisted to fit in place on said taps. 110
- 55 18. In a resistance device the combination with rows of taps in a plane, of resistance elements connected between said rows and extending perpendicularly to said plane comprising portions attached to said taps and V shaped stiffened portions connecting said attached portions.

ALFRED E. WALLER.
